UNITED STATES PATENT OFFICE

108,482

DESIGN FOR A CLOCK

George H. Stephens, Glencoe, Ill., assignor to
Hammond Instrument Company, Chicago, Ill.,
a corporation of Delaware

Application December 4, 1937, Serial No. 73,364

Term of patent 14 years

To all whom it may concern:

Be it known that I, George H. Stephens, a citizen of the United States, residing at Glencoe, in the county of Cook and State of Illinois, have invented a new, original, and ornamental Design for a Clock, of which the following is a specification, reference being had to the accompanying drawing forming part thereof.

Figure 1 is a front elevation; and
Figure 2 is a side elevation of the clock.

I claim:
The ornamental design for a clock as shown.

GEORGE H. STEPHENS.
